UNITED STATES PATENT OFFICE.

CHARLES B. GRAY AND WILLIAM E. TETER, OF DALLAS, TEXAS.

ADJUSTABLE HEADLIGHT FOR VEHICLES.

1,105,973.

Specification of Letters Patent. Patented Aug. 4, 1914.

Application filed May 5, 1913. Serial No. 765,700.

To all whom it may concern:

Be it known that we, CHARLES B. GRAY, and WILLIAM E. TETER, citizens of the United States, residing at Dallas, in the county of Dallas and State of Texas, have invented certain new and useful Improvements in Adjustable Headlights for Vehicles, of which the following is a specification.

Our invention relates to a new and useful vehicle headlight, and its object is to provide a headlight, the reflector of which will be adapted to pivot about a vertical axis, so that the light may be thrown at an angle with the direction of travel if desired.

15 A further object is to provide a device of the character described that will be strong, durable, simple and efficient and comparatively easy to construct and also one that will not be likely to get out of working order.

20 With these and various other objects in view, our invention has relation to certain novel features of the construction and operation, an example of which is described in 25 the following specification, and illustrated in the accompanying drawing, wherein:

Figure 1 is a front view of our headlight. Fig. 2 is a vertical sectional view of the same, the section being taken upon the line 30 $x-x$ of Fig. 1. Fig. 3 is a detail sectional view showing one of the rollers which adapt the reflector to be turned about a vertical axis.

Referring now more particularly to the drawing, wherein like reference characters designate similar parts in all the figures, the numeral 1 denotes the headlight casing and 2 designates a circular plate secured to the floor of said casing. Upon the plate 2 35 is concentrically mounted a second circular plate 3 supported adjacent to its periphery by a plurality of rollers 4 recessed in the plate 2. The plates 2 and 3 are held in a concentric relation by a plurality of bracket members 4^a secured to the plate 2 and overhanging the edge of the plate 3. A conical

reflector 5 having its axis horizontal is supported at an elevation above the plate 3 by a pair of bracket members 6. The numeral 7 denotes a pair of carbons mounted within the reflector and adapted to produce an arc light. The casing 1 is provided at its forward end with the usual glass window 8. A lever 9 projects rigidly in a rearward direction from the plate 3 and is adapted to communicate a partial rotation to the rigidly connected parts 3, 5 and 6. Any desired mechanism may be employed to actuate the lever 9.

The above described headlight is particularly adapted for use upon locomotives to enable the engineer to illuminate any curved portion of the track ahead of the engine. It is to be observed however that the idea is also applicable to street cars, automobiles 65 and other vehicles.

Our invention is presented as including all such modifications and changes as properly come within the scope of the following claim.

What we claim is:

A headlight comprising a casing, a circular plate mounted on the floor of said casing, a second circular plate concentrically mounted upon the first plate and supported adjacent to its periphery by rollers recessed in the first plate, a plurality of bracket members secured to the first mentioned plate and overhanging the second, preventing lateral displacement of the rotatable plate, 80 a reflector mounted upon the rotatable plate at an elevation thereabove, and means for manually rotating the rotatable plate.

In testimony whereof we have signed our names to this specification in the presence of 85 two subscribing witnesses.

C. B. GRAY.

WILLIAM E. TETER.
